Primary Examiner—Catherine R Oliver(74) *Attorney, Agent, or Firm*—Fraser Clemens; Martin & Miller LLC; Donald R. Fraser(57) **CLAIM**

The ornamental design for an artificial reef, as shown and described.

DESCRIPTION

FIG. 1 is a perspective view of an artificial reef embodying the features of the new design;

FIG. 2 is a front elevational view thereof, the left side elevational view, the right side elevational view, and the rear elevational view are identical to FIG. 2;

FIG. 3 is an elevational view of the artificial reef midway between adjacent outwardly extending members to more clearly illustrate the new design;

FIG. 4 is a top plan view thereof; and,

FIG. 5 is a bottom plan view thereof.
